TONGS HAVING RELEASEABLE LOAD
ENGAGING TINES

Edward Kupka, Buckley, Wash.

Application May 22, 1950, Serial No. 163,469

2 Claims. (Cl. 294—118)

1

My invention relates to tongs; more particularly my invention relates to tongs having directly releasable load engaging tines or teeth.

A primary object of my invention is to provide tongs having releasable tines and of such sturdy and simple construction to be particularly useful in the logging industry as skidding tongs.

A further primary object of my invention is to provide a skidding tong which will release its load although the legs of the tong may be wedged between other logs in the pile to which the load has been transferred.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings, Figure 1 is a side elevational view of a device embodying my invention illustrating the tong teeth or tines in open or load-releasing position in dotted lines and in closed or load-engaging position in full lines;

Fig. 2 is an enlarged fragmentary side elevational view of the same, illustrating the load carrying end portion of a tong leg member and illustrating a tine in open or load-releasing position in dash lines and in closed or load-engaging position in full lines;

Fig. 3 is a cross-sectional view taken substantially on broken line 3—3 of Fig. 2; and

Fig. 4 is a cross-sectional view taken substantially on broken line 4—4 of Fig. 3.

Referring to Fig. 1, leg members 5 and 6 are mutually pivotally connected one to the other at their upper portions as by pin means 9 and thus are provided usual portions 7 and 8 which are connected to any suitable hoisting line (not shown) and which hoisting line causes leg members 5 and 6 to move toward each other when it is moved upwardly.

Tines 10 and 11 respectively are pivotally connected with lower end portions 12 and 13 respectively of hook arm members 5 and 6 respectively as by pins 13a. Each side of the lower end portions 12 and 13 of leg members 5 and 6 respectively carry recessed grooves generally numbered 14, which grooves may be provided as by milling or casting.

2

The leg members 5 and 6 are paired but may be otherwise identical and therefore for purposes of illustration and description, leg 6 alone will be treated in detail.

5 Referring to Fig. 3, tine 11 is bifurcated and the legs thereof abut against the lateral walls 16 and 17 of lower end portion 13 of leg member 6.

Referring now to Fig. 2, spring means may be employed to return the tine 6 to the load-engaging position as spring means 18, one end portion of each spring 18 is fixedly connected with pin 13a, which pin serves to pivotally connect tine 11 with the lower portion 13 of leg member 6. The other end portion of each spring 18 is connected with tine 11. The pin 13a is fixedly secured to the lower end portion 13 of leg member 6 and serves as a bearing surface for tine 11 which pivots on said pin 13a.

Tine 11 is provided with recesses 19, which recesses come into alignment with recessed grooves 14 in the lower end portion 13 of leg member 6 as the tine 11 is pivoted into the raised or load-engaging position indicated by full lines in Figs. 1 and 2.

20 23 Lugs 20 are provided of a high shear test material and are slidably carried in the lower end portions of recessed grooves 14 and the lower portions of said lugs 20 are also slidably into the recesses 19 in tine 11 when the recesses 19 are aligned with the lower end portions of recessed grooves 14, that is, when the tine 11 is in the raised or load-engaging position.

25 Resilient means, as springs 21, resiliently urge blocks 20 into the recesses 19 in tine 11 when the tine 11 is in the load-engaging position thus engaging tine 11 with leg member 6. Springs 21 are preferably kept under compression, the upper end portions of each of said springs 21 abutting against shoulders 22 at the top of recessed grooves 14, the lower end portions abutting against lugs 20. Compression of springs 21, not only urges the lugs 20 into recesses 19 when the tine 11 is in load-engaging position, but also tends to maintain the lugs 20 in such position.

40 45 Springs 21 lie within the grooved recesses 14 in the lower end portion 13 of leg member 6. Bars 23 may be fixedly mounted on the lower end portions 13 of leg member 6 in such positions that they serve to retain lugs 20 within the recessed grooves 14 and also within the recesses 19 when said recesses 19 are in alignment with recessed grooves 14.

50 55 The release cables 24 may be directly connected to lugs 20 but preferably rods 25 are fixedly connected with lugs 20. The rods 25 extend up-

wardly within the springs 21 and are connected with release cables 24. Guide members 26 may be fixedly connected to leg member 6 (see Fig. 1) to serve as cable guides.

The mode of operation of my invention is as follows:

A log is engaged in the tong by tines 10 and 11 with said tines in the raised or load-engaging position, i. e., with the lugs 20 in the recesses 19 of tines 10 and 11. The load is then transferred to the desired location and the tines are permitted to angularly move by exerting tension on cables 24, which tension results in an upward movement of rod members 25, further compressing springs 21 and causing lugs 20 to be removed from the recesses 19 in the tines 10 and 11, thus resulting in a free pivotal movement of tines 10 and 11 with respect to the lower portions 12 and 13 of the legs 5 and 6, which pivotal movement is restricted only by the force of springs 18 tending to move the tines 10 and 11 toward raised or load-engaging position. The force exerted by the springs 18, however, is easily overcome by the weight of the load carried by tines 10 and 11, which tines thus pivot downwardly into the dropped or load-releasing position indicated by broken lines in Figs. 1 and 2. As soon as the load is free of the tines 10 and 11, springs 18 urge the tines 10 and 11 into the raised or load-engaging position, in which position spring members 21 force lugs 20 into the recesses 19 in tines 10 and 11. The tong is thus ready to engage another log.

It is to be particularly noted that my invention employs no latch mechanism which either in the load-engaging position, in the load-releasing position, or in movement between the two positions projects beyond the confines of the recesses provided for the latch mechanism in the legs 5 and 6 and in the tines. Therefore, the tines of my invention can be released, and the tong freed of its load even though the tong may be wedged between logs.

Obviously, changes may be made in the form, dimensions and arrangement of the parts of my invention, without departing from the principle thereof, the above setting forth only a preferred form of embodiment.

I claim:

1. In combination with a skidding tong having legs interconnected intermediate their lengths and having recessed grooves at the load receiving end portions of the tong legs; tines pivotally connected with the load-receiving end portions of said legs, each of said tines having a recess in an edge portion thereof, each of said recesses being movable into registration with one of said recessed grooves in said tong legs; lug means slidably mounted in each of said recessed grooves in said tong legs and of a size to slidably interfit a recessed groove in a tong leg; resilient means resiliently urging said lug means into said recesses in said tines when said recesses are in registration with said recessed grooves; and resilient means connected with said tines urging said tines toward load-engaging position.

2. In combination with a skidding tong having legs interconnected intermediate their lengths and having recessed grooves at the load-receiving end portions of the tong legs; tines pivotally connected with the load-receiving end portions of said legs, each of said tines having a recess in an edge portion thereof, each of said recesses being movable into registration with one of said recessed grooves in said tong legs; rod means slidably mounted in each of said recessed grooves; lugs connected with each of said rod means and slidably mounted in said recesses in said tong legs and of a size to slidably interfit a recessed groove in a tong leg; compression spring means surrounding each of said rods and resiliently urging said lug means into said recesses in said tines when said recesses are in registration with said recessed grooves; and resilient means connected with said tines urging said tines toward load-engaging position.

EDWARD KUPKA.
